UNITED STATES PATENT OFFICE

2,207,184

METHOD OF CONDITIONING WELLS

Harry Calvin White, Los Angeles, Calif.

Application September 29, 1937, Serial No. 166,389

9 Claims. (Cl. 166—21)

This invention has to do generally with the art of conditioning oil wells with the view of increasing the ultimate production of a well by initially placing it, particularly the oil producing zone, in a condition such that later, when production has diminished below the potential productivity of the well by reason of the accumulation of clogging bodies of any nature within the producing zone, that zone may again be opened 10 in a simple operation to restore potential production.

First I place the producing region of the well in a condition favorable to maximum initial and continued production by insuring open porosity 15 between the oil sands and the inlet or inlets through which the oil flows into the well pipe. For this purpose I may use a foraminite body of material comprising suitable size (for example gravel size) particles of shape and size most 20 advantageous for the purpose, and which may be placed by any suitable method between the oil sands and the well pipe oil inlet or inlets. For example, the foraminite material may be placed within an underreamed and enlarged diameter 25 portion of the well bore surrounding the usual perforated well pipe or liner, by any suitable method, as for instance that disclosed in Patent No. 2,083,625, issued June 15, 1937, to me on Method of depositing foraminite bodies around 30 well casing. In this manner, I initially place the production zone between the oil sands and well pipe in a condition that will simulate and perhaps exceed the most favorable condition that might exist in a natural formation.

The invention however is more particularly concerned with the function that the foraminite material shall later serve, after its interstitial spaces have become clogged, when acted upon in the manner hereinafter explained. Briefly, my 40 object is to predetermine the nature or composition of the foraminite material with relation to a treating agent, or type of agent, so that when later acted upon by that agent, the material will be affected, physically or chemically, to open the 45 interstitial pores to such an extent that the clogging bodies will be removable by the natural flow from the formation, or by artificial flushing. Generally speaking, I aim to accomplish by the treatment of the foraminite material with the 50 agent, a substantial reduction in the particle size and resultant increase in the size of the interstices. The reduction in particle size may come about by partial dissolution in or by the treating agent, or by chemical reaction with the agent, 55 in which there may occur a simultaneous evolu-

tion of gas that will further aid in flushing the interstices.

As indicated, one of my major objects is to predetermine the composition of the foraminite material so that, contemplating future treatment 5 of the material, the effect of the treating agent upon it will be known in advance. The placement of materials, such as gravel, around the perforated section of a well pipe is known in the art, but to my knowledge it has not been proposed, looking 10 ahead to the future reconditioning of the well, to use a selected material that will be acted upon in a predetermined way by a predetermined type of treating agent. In this general connection it should be mentioned that common siliceous 15 gravel, at least alone, is not suitable for my present process because of the extreme insolubility and chemical inertness of the gravel due to its high content of silica or silica compounds, or the condition in which the silica is present. Moreover, I find it advantageous to use different and 20 preferably prepared materials because of the possibility of predetermining the shape of the particles to give greater interstitial openings and also to cause the material to be acted upon most 25 effectively by the treating agent. It should be understood that I may use a silica containing material, such as siliceous limestone, providing that material is capable of being affected in the desired manner by the treating agent, but, as stated, 30 the usual siliceous gravel heretofore proposed is not suitable for the reasons stated.

It is believed that the general class of materials suitable for use as the foraminite oil passing medium will be understood from the foregoing, although certain typical examples may be given as illustrative. I may use a suitable metal or metal alloy such as aluminum and aluminum alloys, formed in particles of suitable shape. Light weight metals of this character may be particularly desirable when the material is to be deposited around a perforated pipe by upward movement in a stream of heavy fluid such as 40 circulating mud. Particular metals may be selected with relation to the well pipe metal with 45 the view of avoiding or reducing any galvanic action that would bring about reduction or corrosion of any of the metals when an electrolytic condition exists in the well. Instead of metals, I may use substances or compounds such as the 50 alkali earth carbonates, (e. g. calcium carbonate) which when acted upon by an acid reagent will result in an evolution of gas. The particles advantageously may be made substantially spherical in form to provide for open porosity between the 55

particles, desirable particle strength, and large surface exposure to the treating agent when the latter is introduced to the material.

The type of reagent to be employed in the treatment of the material will of course depend upon the particle composition to the extent that the reagent will be capable of acting upon the particles to materially reduce their size. Thus, the reagent may be a solvent for the particles or it may be chemically reactive therewith; and when an acidic material is used the reagent may be alkaline, or acidic when the material is alkaline. Generally, acid reagents are preferred. As to the specific materials referred to above, acid reagents such as aqueous solutions of hydrochloric, sulphuric or nitric acid, will react with the metals and will also react with the alkaline earth carbonates to liberate carbon dioxide gas. Before or while treating the material with the reagent, the material may be treated with a suitable solvent such as a light petroleum fraction, toluene or the like, to dissolve asphaltic or waxy bodies that might interfere with the desired action of the reagent on the material. After a solvent treatment, the reagent may then be forced into the material under pressure, or circulated through the material, until the action of the reagent is complete to the extent desired, which ordinarily will be when a substantial reduction in the particle size will have occurred. If necessary the reagent may then be flushed out of the material.

The invention will perhaps be understood more fully and to better advantage by describing a typical and illustrative method of placing the foraminous material between the oil producing sands and the perforated portion of a well pipe or casing, bearing in mind however that the invention is not to be regarded as limited to any particular method of placing the material in the well. Throughout the description, reference is made to the accompanying drawing, in which:

Fig. 1 is a general view showing a typical casing string containing a charge of foraminous material;

Fig. 2 is a view similar to Fig. 1 showing the material placed about the perforated section of the casing;

Fig. 3 is a view similar to Fig. 2 showing the material deposited within an underreamed section of the well bore, with the casing cemented-off below the material;

Fig. 4 shows a string of tubing and plunger run into the well for the purpose of introducing a solution or reagent for the treatment of the foraminous material; and

Fig. 5 is a fragmentary enlarged view showing the preferred, substantially spherical form of the foraminous material.

In Fig. 1, I show a typical string of casing 10 having at its upper end the usual head 11 having fluid inlet 12 and outlet 13. At its lower end the casing carries the usual or any perforated section 14 at the upper end of which may be provided a suitable barrier, such as closely and circularly spaced bowed elements 15, that will permit upward circulation of fluid around the casing but which will arrest upward displacement of the deposited foraminous material. The material 16 to be deposited around the perforated section 14 of the casing may be introduced directly into the top of the casing in any suitable manner, either preceded by a plug 17, or followed by a plug 18, or both. At the outset, the casing 10 may be raised off bottom so as to give

ample clearance at the lower end of the perforated section for outward and upward displacement of material 16, and to provide any necessary space below the pipe to accommodate either or both of the plugs 17 and 18.

The material 16 is forced downwardly through the casing string and out the lower end of the perforated section 14 by pumping into the casing a column of circulating fluid 20. Plug 17, if used, is forced out the lower end of the perforated section 14, permitting the subsequently discharged material 16 to be carried outwardly and upwardly to space 21 between the section 14 and the well bore wall 22 which, as previously indicated, extends through or within the oil sand or production zone. Pumping of fluid 20 into the casing is continued, causing the material 16 to be discharged from the perforated section 14, followed by plug 18, if used. While for the purpose of illustrating one method of operation I have shown both plugs in Fig. 1, for the purposes of Fig. 2 it may be assumed that only the upper plug 18 is used and that the density of the material 16 with relation to the specific gravity of the circulating fluid, which of course may be controlled by the addition of mud, is such that the material will be substantially floated in the fluid.

By continued operation of the circulating fluid pumps, the fluid is caused to circulate upwardly through space 24 around the casing to the ground surface, and a sufficiently high fluid velocity is maintained to effectively aid in carrying or floating the particles of the material 16 upwardly to the barrier 15, so that the material may substantially fill the space 21 around the perforations 14a. Where the material 16 consists of light weight particles, or any weight particles that do not substantially exceed in density the specific gravity of the circulating fluid, the particles will be floated upwardly into place about the perforations. For the purpose of compacting the particles in the mass 16, the casing string may be vertically reciprocated during the process of placing the material. Thereafter, the casing may be set down on the bottom of the hole (the plug may be removed or drilled through if necessary), or the lower portion of section 16 cemented-off below the perforations.

As illustrated in Fig. 5, the individual particles 16a preferably will be made substantially spherical in form and of such size as to provide open porosity through the interstitial spaces 25 between the particles. The bed of material 16 thus initially provides a foraminous medium through which the oil may readily pass from the formation into the perforations 14a.

Fig. 3 shows the foraminous material deposited as described above, within an underreamed and enlarged diameter section 26 of the well bore 60 containing the perforated section of the casing. Here the shoulder 27 formed by the underreaming operation presents a barrier against upward displacement of the foraminous material beyond the underreamed section of the hole. Sufficient material 16 may be introduced to completely fill bore 26 from the lower end of the perforated casing section 16, and the casing then set on bottom as indicated by the dot-dash lines in Fig. 3, or the lower portion of section 16 below the 70 perforations may be cemented-off as indicated at 28.

Assuming the well, initially conditioned as described above, to have been put on production and eventually the interstitial spaces 25 between 75

the particles 16a to have become clogged to the extent of seriously diminishing the productive capacity of the well, the material 16 may then be treated with reagent by any suitable method 5 to open the interstices in the manner previously discussed. To illustrate, I may lower within the casing a string of tubing 29 carrying at its lower end a plunger 30, through the central passage 31 of which fluid may be discharged within the 10 perforated section of the casing past check valve 32. I may first pump down through the tubing 29 a suitable solvent that will be discharged downwardly into the interior of the perforated section 14, and outwardly against and through the perforations into the material 16 by way of passages 15 33 communicating with an annular groove 34 in the plunger. By reciprocating the plunger through the length of the perforated area of the casing, and at the same time discharging the 20 solvent under pressure through the perforations, I may first flush the foraminous bed 16 to dissolve asphaltic or paraffinic bodies that might interfere with the action upon material by the subsequently introduced reagent.

25 As previously explained, the material composition and type of reagent will have been predetermined to insure that when introduced to the well, the reagent will have the desired action upon the particles 16a of the material. After 30 the solvent treatment, the reagent may be introduced through the pipe string 29 and discharged under pressure outwardly through the casing perforations into the material 16, in the same manner described with reference to the solvent treatment. In this manner the reagent is caused to 35 thoroughly permeate the bed of material 16 and to attack the particles 16a, reducing their sizes and opening up the interstitial spaces 25. The solvent and reagent will also act upon and penetrate the production sands in the bore wall 26, thus opening the formation interstices as well as the spaces between the particles 16a. As will be understood, the reagent may be introduced to the material 16 in quantity and over a period of 40 time necessary to cause a reduction of the particle size to an extent that will restore the desired open communication between the production sands and the casing perforations 14a.

45 After treatment by the reagent, the material 16 may be flushed out by water or other suitable flushing fluid if necessary, although ordinarily the restored natural flow from the formation will suffice to remove the reagent and any desirable reaction products resulting from the action of the reagent on the material.

50 I claim:

1. The method that includes, placing at the outside of an apertured well pipe a foraminous body of well fluid passing material attackable by a fluid reagent to open interstitial spaces within said material, and later, when such spaces have become clogged, introducing said reagent to the well to attack said material and open its interstitial spaces.

60 2. The method that includes, placing at the outside of an apertured well pipe a foraminous body of well fluid passing material, attackable by an acid reagent of the group consisting of

hydrochloric, sulfuric and nitric acids, to open interstitial spaces within said material, and later, when such spaces have become clogged, introducing an acid of said group to the well to attack said material and open its interstitial spaces. 5

3. In the well conditioning art in which there has been placed at the outside of an apertured well pipe a porous body of well fluid passing material comprising particles attackable by a fluid reagent to open the pores of the material; the 10 method of restoring the porosity of said material when it becomes clogged with sand, that includes treating said material with said reagent introduced to the well and thereby reducing the size of said particles to open clogged interstitial spaces 15 between them.

4. In the well conditioning art in which there has been placed at the outside of an apertured well pipe a foraminous body of well fluid passing material including particles chemically attackable by an acid reagent of the group consisting of hydrochloric, sulfuric and nitric acids; the method that includes, treating said material with an acid reagent of said group and by virtue of the resultant chemical reaction opening clogged 25 interstitial spaces between said particles.

5. In the well conditioning art in which there has been placed at the outside of an apertured well pipe a foraminous body of well fluid passing material including particles attackable by an acid 30 reagent of the group consisting of hydrochloric, sulfuric and nitric acids; the method that includes, treating said material with an acid reagent of said group by forcing the acid out through the pipe perforations into said material 35 and thereby reducing the size of said particles to open clogged interstitial spaces between them.

6. The method that includes, placing at the outside of an apertured well pipe a foraminous body of well fluid passing material containing an 40 alkaline earth metal carbonate attackable by an acid reagent to open interstitial spaces within said material, and later, when such spaces have become clogged, introducing said acid to the well to attack said material and open its interstitial 45 spaces.

7. The method that includes, placing at the outside of an apertured well pipe a foraminous body of well fluid passing medium comprising silica and a soluble material attackable by a fluid 50 reagent to open interstitial spaces within said medium, and later, when such spaces have become clogged, introducing said reagent to the well to attack said soluble material and open said interstitial spaces. 55

8. A foraminous pack for wells comprising a porous body of material comprising silica and a solid soluble substance, said soluble substance being adapted to be dissolved to open interstitial spaces in said body after such spaces have become clogged. 60

9. A foraminous pack for wells comprising a porous body of material comprising silica and an alkaline earth metal carbonate, said carbonate being adapted to be dissolved to open interstitial 65 spaces in said body after such spaces have become clogged.

HARRY CALVIN WHITE.
